UNITED STATES PATENT OFFICE.

WILLARD F. RICHARDS, OF DEPEW, NEW YORK, ASSIGNOR TO GOULD COUPLER COMPANY, OF NEW YORK, N. Y.

ANTICREEP DEVICE.

1,189,387.

Specification of Letters Patent.

Patented July 4, 1916.

Application filed October 1, 1915. Serial No. 53,627.

To all whom it may concern:

Be it known that I, WILLARD F. RICHARDS, a citizen of the United States, residing at Depew, in the county of Erie and State of New York, have invented a new and useful Improvement in Anticreep Devices, of which the following is a specification.

This invention relates to improvements in railway car couplers, and more particularly 10 to means employed in connection with car couplers having gravity-actuated knuckle locks, for preventing the locks from creeping or jumping out of their locking positions owing to the jarring or shocks to which the 15 couplers are subjected in service.

The object of the invention is to provide reliable means of very simple and inexpensive construction which will positively retain the lock in its locking position and prevent 20 it from jumping or creeping out of such position in the use of the coupler.

In the accompanying drawings: Figure 1 is a longitudinal sectional elevation of a car coupler provided with means embodying the 25 invention for preventing the creeping or jumping of the knuckle lock out of its operative position. Fig. 2 is a fragmentary longitudinal sectional elevation thereof showing the parts in a different position to 30 prevent creeping. Fig. 3 is a fragmentary longitudinal sectional elevation thereof showing the parts in position to raise the lock. Fig. 4 is a fragmentary transverse sectional elevation thereof on line 4—4, Fig. 1.

35 A represents the head of a car coupler, B the knuckle, C the knuckle lock, and D a hollow horn or projection extending upwardly from the head and into which the lock is adapted to be lifted when moved out 40 of engagement with the knuckle. The coupler shown is of the general construction disclosed in Patent No. 1,132,383, dated March 16, 1915, but the anti-creeping means shown are not limited to use on couplers 45 of this construction but are applicable to couplers of other construction having locks which are lifted out of locking engagement with the knuckle.

The means employed for lifting the lock 50 and for preventing it from creeping or being moved upwardly by the shocks or vibration of the coupler comprise two pivotally connected lifting links, the lower of which is pivoted to the knuckle lock, and the up-

per of which is connected to a lock-lifting 55 shaft or device of any suitable kind. The two links are adapted to swing relative to each other about the pivot joint connecting the same in such a manner that the lower link will engage with shoulders or parts on 60 the coupler head at opposite sides of the hole in the coupler head through which the links extend.

E and F represent respectively upper and lower links which are pivotally connected 65 and by means of which the knuckle lock is lifted for releasing the knuckle. The links extend through a hole e in the top wall of the coupler head and the upper end of the upper link E may be connected with any 70 suitable means (not shown) for lifting the lock. The lower link F is provided at its lower end with an eye f, preferably formed by bending the reduced lower end of the link into a loop, which is interlinked with an 75 eye f' formed on or secured to the knuckle lock so that the lower link is free to swing in an upright plane substantially parallel with the longitudinal axis of the coupler. The upper link E in the construction shown 80 has a bifurcated lower portion e' which straddles the upper end of the lower link and through which a pivot e² connecting the two links passes. When it is desired to lift the lock, the upper link is pulled upwardly 85 by the lifting device and the two links will be moved into vertical alinement, as shown in Fig. 3, in which position the lower link can pass through the hole e in the top wall of the coupler. When the upward pull on 90 the two links is released, they will take one of the positions shown in Figs. 1 and 2, in which the lower link occupies either a rearwardly or a forwardly inclined position. The lower link is provided at its upper end 95 with opposite shoulders f² and f³ and when the link is in either of the inclined positions shown in Figs. 1 and 2 one of these shoulders will be beneath and adapted to strike the top wall of the coupler head at one side 100 of the hole e. Any movement of the lock upwardly, either due to a gradual creeping of the lock or to a sudden shock, will be opposed by the engagement of the shoulders f² and f³ with the lower face of the top wall 105 of the coupler.

The lower link F is largest and heaviest at its upper end, being preferably tapered

downwardly from its upper end, and tends to fall either forwardly or rearwardly to and normally remain in one or the other of the two inclined holding positions shown in 5 Figs. 1 and 2. If for any reason the links do not flex at their joint e^2 when the lock has been lowered to its locking position, but retain the vertical position shown in Fig. 3, a shock acting lengthwise of the coupler in 10 either direction will cause the links to flex and swing the lower link to either its forwardly or rearwardly inclined position, in which it will engage the top wall of the coupler head and hold the lock down. On the 15 other hand, if the lower link is thrown out of one of its inclined positions by a shock on the coupler the link will either fall back to the same position or to its other inclined position, and in either event will effectually 20 prevent the accidental lifting of the lock.

The device is thoroughly reliable in operation, since shocks in either direction would move the links into their operative positions before causing the lock to jump 25 or creep upwardly.

I claim as my invention:

1. The combination with a car coupler having a vertically movable knuckle lock, of two pivotally connected links for lifting 30 said lock, the lower of said links being pivotally connected at its lower portion with said lock and being adapted to swing forwardly and rearwardly from an upright position to different holding positions, said 35 links being drawn into substantially vertical alignment for lifting the lock, and parts on the coupler head adapted to engage said lower link when the same is in either of its

holding positions to prevent said lower link and said lock from moving upwardly. 40

2. The combination with a car coupler having a hole in the top wall of its head, and a knuckle lock which lifts for releasing the knuckle, of two pivotally connected links adapted to move through said hole for 45 lifting the lock, the lower of said links being pivotally connected at its lower portion to said lock and being adapted to swing forwardly and rearwardly from an upright position to two different inclined holding positions, said link when in either of said two holding positions being adapted to engage the edge of said hole and prevent the lock from lifting from its locking position. 50

3. The combination with a car coupler having a hollow upwardly extending horn and a vertically movable knuckle lock movable to an unlocking position into said horn, of two pivotally connected links in said horn for lifting said lock and adapted to pass 60 through a hole in the top of said horn for lifting said lock, the lower of said links being pivotally connected at its lower portion with said lock and being adapted to swing forwardly and rearwardly from an upright 65 position, parts of said hollow horn being adapted to engage the lower link when in its forward or rearward position to prevent the link and lock from moving upwardly.

Witness my hand, this 29th day of September, 1915. 70

WILLARD F. RICHARDS.
